UNITED STATES PATENT OFFICE.

PHILIPP ANTON ADELMANN, OF METZ, GERMANY.

APPARATUS FOR REMOVING THE WASTE LIQUIDS FROM VAGINAL INJECTIONS.

SPECIFICATION forming part of Letters Patent No. 425,559, dated April 15, 1890.

Application filed October 2, 1889. Serial No. 325,814. (No model.)

To all whom it may concern:

Be it known that I, PHILIPP ANTON ADELMANN, doctor of medicine, physician, a subject of the Emperor of Germany, residing at Metz, Germany, have invented a new and useful Apparatus for Removing the Waste Liquid from Vaginal Injections, of which the following is a specification.

This invention has for its purpose to remove the inconveniences attendant on the usual mode of administering injections into the vagina by means of the irrigating apparatus. These injections are generally applied to the person when in a sitting or cowering posture, which is not only very inconvenient, but also prejudicial to a perfect attainment of the desired purpose, which can only be insured by making said injections while the person occupies a more or less horizontal position. This leads generally, particularly when large quantities of liquid are employed, to moistening the dress, bedding, or room, or it necessitates the attendance of another person for pressing down the fore edge of and emptying the bed-vessel.

The apparatus forming the object of this invention and intended to obviate the above inconveniences is illustrated in the accompanying drawings, in which—

Figure 1 is a vertical section of the apparatus on the line III, Fig. 2; and Fig. 2, the top view of the apparatus.

Similar letters refer to similar parts throughout the several views.

This apparatus allows vaginal injections to be performed in a recumbent or lying position of the person, while the liquid, even when considerable quantities thereof are employed, is completely drawn off and conducted into a pail or accumulating-vessel, so as to preclude any moistening of the bedding, dress, or room.

The approved apparatus essentially consists of a circular or other vessel A, having at the bottom a muffle *a* for conducting the liquid through an india-rubber or other tube

attached thereto into a pail or other receptacle, and at the top on one side a broad slightly-concave receiving-pan B, the bottom of which gradually ascends outwardly, the sides C C 50 being of triangular shape. The outer edge of said pan is provided with two symmetrically-adjoining segmental recesses C² C², and at the bottom with a cross rib or stay C', secured so as to be tangential to these recesses. 55

To use the improved apparatus, the person lies down crosswise on the bed, puts her legs on chairs on either side of the pail, advances to the edge of the bed and draws the pan so far under her as to cause the point C³, formed 60 by the segmental recesses C² C², to lie closely before the point of the chine-bone, while only the soft or fleshy parts are in contact with the pan B. By the weight of the body the cross-stay *b'* is pressed into the bedding, and 65 thereby secures the apparatus in its position, while the soft or fleshy parts are firmly pressed against the pan B, thus producing a water-tight separation of the apparatus from the bedding. The liquid flowing back from 70 the vagina when using the irrigating device passes over the pan B into the vessel A, and hence through a tube attached to the muffle *a* into the pail or other receptacle.

To facilitate the carrying of the improved apparatus by the physician, the vessel may be made from soft india-rubber or other convenient substance; or the pan B may be secured hinge-fashion to the vessel A to allow the apparatus being folded up. 75

What I claim, and desire to secure by Letters Patent of the United States, is—

In an apparatus for removing the waste liquid from vaginal injections, the combination of the vessel A with the slightly-concave receiving-pan B, the segmental recesses b² b², the point b³, and the cross-rib b', as described, and for the purpose specified. 85

PHILIPP ANTON ADELMANN.
